UNITED STATES PATENT OFFICE

2,077,632

CHANGEABLE EXHIBITOR

Harry V. Marsh, Chicago, Ill.

Application June 10, 1935, Serial No. 25,712

2 Claims. (Cl. 40—28)

This invention relates to improvements in signs, and more particularly, to a type of sign which may be characterized as a variable display or reading exhibitor, the invention having for an object to provide a sign of the stated type wherein display matter or intelligence will be definitely and selectively varied and displayed during its operation, thus producing a multiple or multi-stage exhibition.

10 An equally important object of the invention is to provide a changeable exhibitor capable of producing, through the medium of simple, durable, and stable instrumentalities, a multiplicity or series of pre-arranged displays whereby to accord 15 animation or changeability to said displays, possessive of novel advertising and educational import and value.

It is a more specific object of the invention to provide a variable or changeable exhibitor wherein in a master pattern means is co-operatively associated with an adjustable or movable pattern selector means of such construction that when the latter is moved into or through a pre-determined course of travel with relation to the former, a pre-determined and changeable display will be 25 effected by the master pattern means.

It is furthermore an object of the invention to provide a changeable or variable exhibitor of the character heretofore mentioned, which, by 30 reason of its exceedingly simple construction, may be produced at a minimum of cost, and which, due to its mode of usage, may be advantageously and efficiently operated at a minimum of cost over a prolonged period of time.

35 Yet another object of the invention resides in the provision of a device such as herein referred to, whose province or range of utility will be exceedingly broad, permitting of satisfactory usage of the invention for a substantially unlimited 40 number of advertising, educational, or similar purposes.

Other objects of the invention will be in part obvious and in part pointed out hereinafter.

In order that the invention and its mode of 45 operation may be readily understood by those skilled in the art to which it appertains, I have in the accompanying drawings and the detailed description based thereupon, set out several embodiments of my invention.

50 In these drawings:

Figure 1 is a perspective view of the improved sign, showing it in one stage of operation;

Figure 2 is an enlarged fragmentary rear elevation of the same, showing the mode of construction of the pattern selector means and its

mounting upon and adjacent the supporting body of the sign provided with the master pattern;

Figure 3 is an enlarged fragmentary detail in longitudinal section through the sign, taken on the line 3—3 of Figure 2, looking in the direction 5 in which the arrows point;

Figure 4 is a similar view but wherein the pattern selector means is aligned with certain other openings of the master pattern than those illustrated in the Figure 3;

Figure 5 is an enlarged fragmentary detail in front elevation of a portion of the sign, a part of the facing material of the sign having been removed and showing the master pattern means;

Figure 6 is an enlarged and fragmentary section taken on the line 6—6 of Figure 5, looking in the direction in which the arrows point;

Figure 7 is a front elevation of a modified form of the sign;

Figure 8 is an enlarged detail in elevation having portions broken away, illustrating the movable pattern selector means of that form of the invention disclosed in Figure 7;

Figure 9 is an enlarged fragmentary detail in longitudinal detail taken on the line 3—3 of Figure 7, looking in the direction in which the arrows point;

Figure 10 is a similar view taken along the line 4—4 of Figure 9 and at right angles thereto, showing the master pattern means;

Figure 11 is an enlarged fragmentary detail in elevation of one of the pattern selector means in one stage of adjustment or in one position with respect to the master pattern means, and,

Figure 12 is a similar view showing the pattern selector, as illustrated in Figure 11, in the second or in another stage of its adjusted position with respect to the master pattern means.

Having more particular reference to the drawings, in connection with which like characters of reference will designate corresponding parts throughout, one embodiment of the improved sign, and particularly, that embodiment illustrated in the Figures 1 to 6 inclusive, comprises a sheet-like body portion or face element designated by the numeral 1, adapted to be supported in a vertical or near vertical plane by means of arms 2 suitably hinged to the normally rearward side thereof, retainable in their respective operative positions by means of stay pieces 3, 40 also hinged to appropriate portions of the normally rearward side of the body 1, and having

45 embracing engagement with certain portions of the arms 2, as illustrated in the Figures 1 and 2. Slots are cut in corresponding upper portions of 50 55

the arms 2 and receive a transversely disposed shelf member 4 therein, by means of which an electric incandescent lamp 5 may be supported in proximity to the rear-ward side of the sign body. 5 Of course, various other modes of supporting the sign body portion 1 may be substituted for that shown, such as conditions or preference may dictate.

Formed in the body 1 are a plurality of series 10 of relative concentrically arranged semi-circularly disposed short slots, the slots of one group of series being collectively identified by the numeral 6, and those of the second group being collectively identified by the numeral 7. It will also be noted 15 that the groups of series of slots 6 and 7 are radially spaced with respect to each other and that those identified by the numeral 6 are alternately positioned with relation to the remaining group and are so formatively arranged as to constitute 20 the word "How", or other suitable intelligence, while the group 7 is formatively arranged to constitute the word "Here's", or other suitable intelligence. Other series of circularly or semi-circularly arranged slots 8 and 9 are formed in 25 adjacent portions of the body 1, on either side of the intelligence constituting groups 6 and 7, and as will be noted, the series 8 aligns with one of the series of slots of the group 7, while the series 9 is aligned with one of the series of slots comprehended by the group 6.

If desired, other openings, generally identified by the numeral 10, may be formed in an appropriate portion or portions of the body 1, in the shape of arrows or similar devices, for the purpose of 35 increasing the animate effect produced with operation of the improved sign.

A sheet of translucent material, identified by the numeral 11, is arranged over the normally outer side of the sign body portion 1, as shown 40 in the Figures 1, 3, 4, and 5, the same being secured to adjacent portions of said body by adhesive or some such similar means. In this way, the various slots identified by the numerals 6, 7, 8, 9, and 10, are concealed from the view of an 45 observer of the sign, though it is of moment to note at this point, that where a light is directed onto the reverse or normally inner side of the sign body portion 1, said openings will then be clearly discernible through the translucent sheet 50 11.

The construction thus far described, and particularly, the intelligence constituting groups of slots 6 and 7 and the slots 8, 9, and 10, constitute the master pattern means of my improved sign.

55 Rotatably mounted directly adjacent to the normally inner side of the sign body portion 1 is a disc-like or circular pattern selector 12, the same being preferably constructed of cardboard or other suitably stiff material. To effect rotatable mounting of the pattern selector 12, I engage a bearing sleeve 14 in a portion of the body 1 concentrically of the groups of slots 6, 7, 8, and 9, while another sleeve 15 is concentrically engaged through the pattern selector 12. A stub shaft or similar mounting 13 is rotatably received in the bearing 14 and extends through the sleeve 15, the latter being fixedly connected thereto. Thus, with rotation of the stub shaft 13, it will be seen that the pattern selector 12 will be moved 70 therewith by and over the inner side of the sign body portion 1. A suitable drive (not shown) is adapted to be connected to the shaft 13, whereby rotary motion may be transmitted to it and to the pattern selector 12.

75 To steady or brace the rotatable selector 12

during its period of rotation, I may and preferably secure an arcuate guide bracket 16 to an appropriate portion of the inner side of the body portion 1, said bracket having overlapping engagement with a portion of the pattern selector 12, as 5 shown in the Figures 2, 3, 4, and 5, and by consequence, serving as a means for effectually retaining the selector 12 in direct engagement or contact with the sign body portion 1 during such rotation. 10

The selector 12 is formed with groups of series 15 of circularly disposed slots 17 and 18, the slots of the series group 17 being so arranged that they are radially alternated with respect to the slots of the series group 18. Other and comparatively 20 short semi-circular slots 19 and 20 may be and preferably are formed in portions of the rotatable selector 12, the slot 19 being aligned with certain of the series group 18.

With rotatable mounting of the selector 12 25 upon the sign body portion 1 as hereinbefore described, it will be noted on reference to the Figure 3, that the series group of slots 18 will register or become aligned with the series group of slots 6 formed in the body 1, during the course 30 of rotary movement of said selector, and that the slots of the series group 17 during further rotation of the selector 12, will register or become aligned with the series group of slots 7 in the body 1, as shown in Figure 4. Since the slot 35 19 aligns with certain of the series group 17 and the slot 20 aligns with certain of the series group 18, it will be understood that during rotation of the selector 12, they will, respectively, register with the series of slots 8 and 9 in the sign body 40 upon either side of the series groups 6 and 7.

Differently or correspondingly colored translucent sheets 21 and 22 are engaged over the slots 17 and 19 and 18 and 20 and appropriately secured to adjacent portions of the selector 12 by 45 adhesive or similar means.

If desired, further animation may be accorded the sign by forming arrow-like or otherwise shaped openings, generally designated by the numeral 23 in the selector 12, such openings 45 corresponding in shape and size with the openings 10 hereinbefore referred to, and being substantially radially disposed in stepped fashion with respect to the selector 12. Thus, as the selector 12 is rotated, the different groups of openings 23 will 50 be successively registered with the openings 10 in the sign body portion 1. Translucent colored sheets 24 and 25 may be engaged over all or certain of the openings 23, so that as they become successively registered with the openings 10 during 55 rotation of the selector 12, colored effects will be produced to the eye of an observer.

While I have hereinbefore stated that the translucent colored sheets 21, 22, 24, and 25 are engaged over the openings or slots in the selector 12, it is quite obvious that the arrangement of such colored sheets may be reversed, i. e., that translucent coloring may be presented over those portions of the sheet 11 applied to the face side of the sign body portion 1 directly adjacent the 65 grouped series of circular slots 6, 7, 8, and 9, as well as the openings 10. Moreover, it is to be understood that the intelligence or advertising constituting grouped series of slots 6 and 7 may be varied in their placement or positioning upon 70 the sign body portion 1, without deviating from the province of my invention; likewise, that the arrangement or formation of the slots 6, 7, 8, and 9 and the openings 10 in the sign body portion 1, and the slots and openings 17, 18, 19, 20 75

and 23, respectively, in the rotatable selector 12 may be reversed. That is to say, the former slots and openings may be formed in the selector 12, whereas the latter mentioned slots and 5 openings may be formed in the sign body portion 1.

In operation of the form of exhibitor previously described, the body portion 1 is supported in a vertical or substantially vertical position by 10 means of the hinged arms 2. A light source, such as an electric incandescent lamp 5, is attached to and supported upon the member 4 directly rearwardly of the intelligence constituting groups of slots 6 and 7.

15 The selector 12 is now caused to rotate in a clockwise direction at a comparatively slow but steady rate of speed by a motor or other driving means (not shown) connected to the shaft 13. Assuming that the slot 20 is just to one 20 side of the start of the series of slots 8 in the sign body portion 1, with rotation of the selector in the direction indicated, said slot will be successively registered with said openings 8, permitting light rays emitted from the lamp 5 to 25 be projected through the colored translucent coverings thereof. As rotation of the selector 12 continues, the grouped series of slots 18 therein will be brought into progressive registration with the different successively following letters 30 of the grouped series 7, spelling out the word "Here's". The over-all lengths of the slots 18 are such that they are greater than the over-all lengths of the grouped series 7 constituting the word "Here's", and by consequence, during the 35 movement of the selector 12 in its rotary path of travel, said slots 18 will be registered with the slots making up the entire grouped series 7. As the slots 18 are successively and finally wholly registered with the grouped series of slots 7, light rays emitted from the lamp 5 will be permitted 40 to be projected therethrough, thus, presenting an illuminated sign in form of the word "Here's" upon the face side of the sign body portion 1. The selector 12, being continuously rotated, will 45 have its slots 18 disregistered with respect to the grouped series of slots 7, immediately following which the slots 17 will move into progressive registration with the grouped series of slots 6 in the body portion 1, constituting the word 50 "How", successively spelling out the word, letter by letter, until all of the letters thereof are in registration with these slots 17. During the period of partial, successive, and full registration of the slots 17 with the grouped series of slots 55 6, it will be understood that the light rays emitted from the lamp 5 will be permitted to be projected therethrough, causing the word "How" upon the body portion 1 to be illuminated according to the color of the translucent sheet 21 60 engaged over the slots 17. As rotation of the selector 12 continues, the slot 19 will be brought into successive registration with the slot 9 in the sign body portion 1, and of course, these latter slots will appear in illuminated form on 65 said body portion 1. It will be also understood that during the rotative movement of the selector 12 that the arrow or otherwise shaped openings 23 therein will be successively registered with the correspondingly shaped openings 10 70 in the body portion 1, and light rays from the lamp 5 will be projected therethrough and will be colored according to the color of the translucent sheets 24 and 25 engaged over certain of these openings 23.

75 The operation of the exhibitor, just described,

will continue, repeating the display of advertising matter or intelligence from the face side of the body portion 1.

In the Figures 7 to 12 inclusive I have shown a modified form of the invention. The exhibitor illustrated in this particular form of the invention is adaptable for usage in presenting certain illustrative data to an observer. It consists of a sign body portion 1' of rectangular or other shape, adapted to be supported in a vertical or near vertical position by means of arms 2' hinged to its normally rearward side, which arms are immovably retained in their supporting positions by means of stay pieces 3'. The normally rearward 15 ply of the body 1' has a portion thereof cut away, as indicated by the numeral 26, and the adjacent portion of the remaining ply of the body is formed with semi-circular series of relatively short slots, generally indicated by the numeral 27, intermediately of which other semi-circular series of 20 short slots, generally indicated by the numeral 28, are formed therein.

A circular or disc-like selector 12' is rotatably mounted adjacent the outer side of the body portion 1' by means of a stub shaft 13' or like element connected thereto through a fitting 14' and rotatably received through a bearing sleeve 15' provided in an appropriate portion of the body 1'. A motor or other driving means (not shown) is adapted to be connected to the inner end of 30 the shaft 13', in order that rotary motion may be transmitted to it and to the selector 12'.

The diameter of the selector 12' is such that a part thereof will have overlying relationship with that part of the body 1' having the semi-circularly disposed series of slots 27 and 28 therein.

Affixed to the normally outer side of the selector 12' is a correspondingly shaped sheet of translucent material 29 having certain characters or figures, such for example as ducks in flight, illustrated in the instant embodiment of the invention and designated by the numeral 30, printed or otherwise presented upon its face, together with semi-circular and clockwise pointing arrows or like symbols 31; the Figures 30 being arranged in relatively spaced relation about the selector 12' in proximity to its circumference and the devices 31 being interpositioned with respect thereto.

Substantially segmentally grouped and semi-circular series of openings, generally designated by the numeral 32 are formed in parts of the selector 12' directly adjacent and rearwardly of the Figures 30 presented upon the face of the translucent sheet 29, said openings being preferably covered with suitably shaped pieces of colored translucent material 33 affixed to the normally rearward and adjacent portion of the selector 12'. Other openings, corresponding in size and shape to the openings 32, and designated by the numeral 34, are formed in the selector 12' in proximity to the segmentally grouped semi-circular series of openings 32. These latter openings, as will be noted upon reference to the Figures 8 and 12 are arranged intermediately of certain of the semi-circular series of openings 32. They are covered by a suitably sized and shaped piece of translucent material 35 of a color different from that of the translucent material 33.

In operation of the form of invention disclosed in the Figures 7 to 12 inclusive, a steady and comparatively slow rotary motion is transmitted to the selector 12' through the shaft 13' connected thereto, causing the said selector to be moved in

a clock-wise direction. This movement will cause the Figures 30 presented upon the face of the sheet 29 covering the selector 12' to be moved in an orbital path of travel by the semi-circular series of openings 27 and 28 formed in the sign body portion 1' adjacent the cut-away part 26. During this orbital movement of the figures 30, it will be appreciated that the grouped and semi-circular series of openings 32 formed in the selector 12 directly adjacent each figure, together with their companion openings 34 will be moved over the grouped semi-circular series of openings 27 and 28. During such movement, the openings 32 will be successively registered with the series 15 of openings 27, whereas the series of openings 34 will be successively registered with the series of openings designated by the numeral 28. In this connection, it will be appreciated that because of the mode of arrangement of the openings 34 with respect to the openings 32 in the selector 12', successive registration of said openings 34 with their companionate openings 28 in the body portion 1' will follow the successive registration 20 of the openings 32 with their respective companionate openings 27. As registration of the openings 32 and 27 and 34 and 28 is effected, light rays emitted from an electric lamp designated for convenience by the numeral 36 and arranged in proximity to the cut-away portion 26 of the exhibitor body 1' will be projected therethrough. Due to the arrangement of the differently colored translucent pieces 33 and 35 over their respective openings 32 and 34, different color effects will be shown through those portions of the translucent sheet 29 directly over the openings 32 and 34.

The type of changeable or variable exhibitor described in the latter embodiment of the invention is particularly adaptable for usage in depicting or illustrating the comparative striking efficiencies of the shot or pellets of shot gun shell loads, i. e., the greater number of hits or mathematical chances of hits capable of being effected with a "short shot string" loaded shell, as compared with that of an ordinary load, or as it may be aptly termed a long shot string load. The effective or "hit" registering pellets of the different types of shot gun shell loads are depicted by the openings 32 upon the selector 12', which register during their orbital path of movement with the grouped semi-circular series of openings 27, whereas the ineffective pellets or "misses" are depicted by the openings 34 in the selector 12' which register with the openings 28 in the sign body 1'. The "hits" and the "misses" are capable of being readily distinguished by an observer of the exhibitor by reason of the different colors of light rays which will be presented upon those portions of the face of the translucent sheet adjacent the openings 32 and 34, which openings, as heretofore stated, are arranged adjacent to the various figures 30 upon the sheet 29 and are so relatively positioned with respect to such figures that the "hit" depicting openings 60 32 will be very closely or directly positioned with respect to such figures 30, whereas the openings 34 registering with the openings 28 following registration of the openings 32 with the openings 27, will be so arranged with respect to the figures 30

as to clearly establish the same to an observer as "misses".

It will be understood that the modified form of exhibitor may be greatly varied as to its mode of usage; also, that the arrangement of the registering openings 27, 28, 32, and 34 may be greatly changed from that disclosed in the illustrated embodiment without departing from the province of the invention. By the same token, different colored effects may be produced upon the face side of the selector 12', by changing the color of the translucent sheets 33 and 35 as desired.

Manifestly, the constructions shown are capable of considerable modification, and such modification as is within the scope of my claims, I consider within the spirit of my invention.

I claim:

1. A changeable exhibitor comprising a master pattern means having a plurality of groups of openings formed therein, the openings of one group being located in planes different to those in which the openings of another group are located, and a continuously movable selector means co-operatively associated with said master pattern means, said selector means having a plurality of groups of openings formed therein, the openings of one of said groups in said selector means being arranged in planes different to those in which the openings in another group in said selector means are arranged, the openings in said selector means being adapted to be progressively registered with the correspondingly arranged openings of certain of said groups of said openings in said master pattern means and permitting the passage of light rays therethrough during continuous movement of the selector means until all of the registering openings in said master pattern means are in registration and visible and maintaining such registration and visibility for a predetermined period of time during the continuous movement of said selector means.

2. A changeable exhibitor comprising a master pattern means having a plurality of groups of openings therein, the openings of one of said groups in the master pattern means being arranged in planes different from those in which the openings of another group in said master pattern means are arranged and a continuously moving selector means co-operatively associated with said master pattern means, said selector means having a plurality of groups of openings of different lengths formed therein, the openings in one of said groups in said selector means being arranged in planes different from those in which the openings of another group in said selector means are arranged, the openings of the different groups in said selector means being adapted to be progressively registered with those openings in said groups in said master pattern means which are located in planes corresponding thereto to permit the passage of light therethrough during continuous movement of said selector means until all of the openings of the registering groups are in registration and visible, and maintaining such registration and visibility for a predetermined period of time during the continuous movement of said selector means.

HARRY V. MARSH.
